UNITED STATES PATENT OFFICE.

JOHN V. McMANIS, OF DAYTON, OHIO.

TREATMENT-STOOL.

1,326,943.

Specification of Letters Patent.

Patented Jan. 6, 1920.

Application filed March 7, 1917. Serial No. 153,146.

To all whom it may concern:

Be it known that I, JOHN V. McMANIS, a citizen of the United States, residing at Dayton, in the county of Montgomery and 5 State of Ohio, have invented certain new and useful Improvements in Treatment-Stools, of which the following is a specification.

My invention relates to improvements in 10 treatment stools for use of osteopaths and other drugless healers. One of its objects is to provide a stool having an adjustable seat for the patient, a foot rest for the patient, and a foot rest for the operator, arranged so that the operator may secure a 15 rest at varying heights from the floor for his feet, and thus place himself in position to flex different portions of the spinal column of a patient. Another object is to 20 provide a stool in which the seat is adjustable both vertically and to different positions of inclination. Another object is to provide a stool having an adjustable foot rest for the operator and convenient means 25 to lock and release the adjustable foot rest. Another object is to provide simple and readily portable apparatus by means of which any desired section of the spinal column may be flexed. My invention also 30 comprises certain details of form combination and arrangement, all of which will be fully set forth in the description of the accompanying drawings in which;

Figure 1 is a side elevation of one form 35 of my improved apparatus in position for use.

Fig. 2 is a rear elevation of the same.

Fig. 3 is a plan view of the same.

Fig. 4 is a side elevation illustrating a 40 modification.

Fig. 5 is a plan view of the operator's foot rest of Fig. 4 detached.

Fig. 6 is a detail of the seat inclining and adjusting mechanism.

45 The accompanying drawings illustrate the preferred embodiments of my invention. As illustrated in Figs. 1, 2 and 3, A represents the base. B represents a standard, preferably of rectangular cross section seated in a corresponding vertical recess in 50 the base A, and adjustable as to height relative to the base, and locked to its adjusted position preferably by means of a hand wheel 2 threaded to the base, and a 55 series of recesses 3 in the standard B to re-

ceive the end of the threaded shank of the hand wheel. At the upper end of the standard B is a head 4 having a pair of ears 5 at one side and a pair of ears 6 at the other side. A seat D preferably upholstered is 60 provided on its under side with a pair of ears 7 pivotally connected to the ears 5 of the head 4. The seat D has also pivotally connected to its under side a pair of short links 8 which at their opposite ends engage 65 eccentrics 10 carried by a square shaft 9 and with hubs 10' journaled in the ears 6 of head 4. A hand lever 12 enables the shaft 9 and eccentrics 10 to be rotated against a friction brake or locking member 14 to adjust the seat to various positions of inclination relative to a normal horizontal position, either toward the front or rear. The rectangular shank of standard B prevents the seat rotating thereon relative to base A. 70 The base carries a U-shaped foot rest 15 for the feet of the patient to rest upon and secure for the patient a firm position upon the seat D. The base A has a rearwardly projecting bracket 16 which at its rear end has 75 a pair of forked arms 17 provided with ears 18. A yoke shaped foot rest 22 for the operator is pivotally connected to the base at 19, and projects rearwardly, being provided with one or more pairs of foot rests 80 or stirrups 20 to receive the toes of the feet of the operator. Links 21 are connected at one end to the foot rest 22 and at the opposite end to the upper end of a rectangular bar 24 which slides vertically between the 85 forked arms 17. A locking member 25 having a rectangular recess therein for the passage of the bar 24, is pivotally connected to the ears 18, so that actuated by gravity it will tend to assume an inclined position and 90 bind upon the bar 24 where it passes through the rectangular recess in the locking member 25, and which is at one side of the pivotal point 18, thereby serving to lock the bar 24 automatically against movement downwardly, but leaving it free to move upwardly. An actuating lever or projection 95 26 on member 25 enables the operator to lift the member 25 with the toe of one foot and thus release the locking effect on bar 100 24, while by means of his other foot in one of the stirrups, the foot rest 22 may be lowered to any desired extent. The operator is thus enabled to conveniently adjust the foot rests 22 either upwardly or down- 105 110

wardly, using his feet for that purpose, and to have the foot rest automatically locked to its adjusted position. By employing one or more sets of stirrups 20 on the foot rest lever, a wide range of positions vertically for the feet of the operator is attainable.

Strap-loops 34 are preferably attached to seat D to enable one or more straps 35 to be employed if desired to assist in retaining the patient in position on the stool. The upper face of seat D is preferably of the outline illustrated with a centrally depressed section and a raised rear section *d* and a raised forward section *d'* to assist the patient in retaining a firm position on the seat D and prevent any tendency to slip therefrom either forwardly or rearwardly.

In practice the patient is seated upon the seat D with his feet on the foot rest 15, and his heels engaged against the inner face thereof. The operator takes a position seated upon a table E or other object of greater elevation than the seat D, and with his feet in one pair of stirrups, and by adjusting the stirrups vertically relative to the seat D is enabled to rest his knees as a support or leverage against different portions of the spinal column of the patient, and by placing his hands on the shoulders or other upper portions of the patient to articulate and exercise any desired section or sections of the patient's spine.

In the modification shown in Figs. 4 and 5 I have illustrated a bar 30 adjustably and pivotally secured at 32 by means of a hand locking wheel 33 to the outer end of bracket 16', similar to bracket 16 of Fig. 1. The bar 30 carries a series of horizontal cross-bars 31 each of which may serve as a support for the feet of the operator and enable him to secure a high or low support for his feet by changing them from one rod 31 to another. The pivotal adjustment of bar 30 enables the same to be adjusted to different positions of inclination upon the center 32 to secure the desired relation of the bar 30 and rods 31 relative to the stool, and when using the lower rods 31 to avoid contact of the upper portion of bar 30 or rods 31 with the legs of the operator.

Fig. 6 illustrates partly in section an eccentric shaft and its connections, constituting the preferred form of mechanism for securing a horizontal or inclined position of the seat in either Fig. 1 or Fig. 4.

The mechanism herein illustrated and described is capable of considerable modification without departing from the principle of my invention.

Having described my invention, what I claim is:

1. A treatment stool comprising a base, a vertically adjustable standard mounted upon said base to non-rotatably support a seat, a backless patient's seat mounted upon

said standard and tilttable fore-and-aft relative thereto to different positions of inclination, and means carried by and at the rear of the stool to support the feet of an operator, the foot-engaging parts thereof lying in a plane above the base and below the seat to enable the operator to bring his knees to bear against the back of the patient.

2. A treatment stool comprising a base, a foot rest for a patient carried thereby, a backless seat rigidly supported upon said base, and means carried by said stool at the opposite side from said patient's foot rest to afford a support for the feet of an operator at different positions vertically relative to said base, said foot-rest being so positioned at a point above the base as to permit the operator in each position to bring his knees to bear against the back of the patient.

3. A treatment stool comprising a base having a backless seat for a patient rigidly supported thereon, a foot rest for a patient at the front of the stool and a foot rest for an operator carried by and at the rear of the stool, said foot-rest being so positioned at a point above the base as to enable the operator to bring his knees to bear against the back of the patient.

4. A treatment stool comprising a base, a backless seat for a patient rigidly supported thereon, and a foot rest for an operator at the rear of said seat supported upon and vertically adjustable relative to said base, said foot-rest being in each of its adjustments so positioned as to enable the operator to bring his knees to bear against the back of the patient.

5. A treatment stool comprising a base, a seat for a patient rigidly supported thereon, a foot rest for an operator supported upon said base at the rear of said seat and vertically adjustable relative to said base, and means releasable by the foot of the operator to lock said operator's foot rest in its adjusted positions.

6. A treatment stool comprising a base, a seat for a patient mounted upon said base, harness-means attached to said seat to retain a patient in position thereon, and means carried by said base to support the feet of an operator at different positions relative to said base.

7. A treatment stool comprising a base, a backless seat for a patient rigidly supported thereon and having a rearwardly-inclined seat-face-section tending to retain a patient in position thereon against pressure from the rear, a foot-rest for a patient at the front of the stool, and a foot-rest for an operator carried by and at the rear of the stool, said foot-rest for the operator being so positioned at a point above the base as to enable the operator to bring his knees to bear against the back of the patient.

8. A treatment stool comprising a base, a seat for a patient mounted upon said base and having a rearwardly-inclined seat-face-section tending to retain the patient in position thereon against pressure from the rear, harness means attached to said seat to pass across the lap of a patient tending to retain a patient in position on said seat, and means carried by said base to support the feet of an operator at different positions relative to said base.

9. A treatment stool comprising a base, a backless seat for a patient rigidly supported thereon and having a forwardly-inclined seat-face-section tending to retain a patient in position thereon against displacement from said seat rearwardly, a foot-rest for a patient at the front of the stool, and a foot-rest for an operator carried by and at the rear of the stool, said foot-rest being so positioned at a point above the base as to

enable the operator to bring his knees to bear against the back of a patient.

10. A treatment stool comprising a base, a backless seat for a patient rigidly supported thereon and having a forwardly-inclined seat-face-section tending to retain a patient in position thereon against displacement from said seat rearwardly, harness means attached to said seat to pass across the lap of a patient tending to retain a patient in position on said seat, and means carried by said base to support the feet of an operator at different positions relative to said base.

In testimony whereof I have affixed my signature in the presence of two witnesses.

JOHN V. McMANIS.
